CLAIM

The ornamental design for an animal waste bag with retaining ring, as shown and described.

DESCRIPTION

FIG. 1 is a top-front perspective view of an animal waste bag with retaining ring, showing my design, the top-rear perspective view being a mirror image thereof;

FIG. 2 is a top-right perspective view thereof;

FIG. 3 is a top-left perspective view thereof;

FIG. 4 is a top view thereof;

FIG. 5 is a bottom view thereof;

FIG. 6 is a top-front perspective view thereof with the retaining rings in a separated position and the bag portion removed; and,

FIG. 7 is a top view thereof with the retaining rings in a folded configuration.

The broken lines depict portions of the animal waste bag with retaining ring that form no part of the claimed design.
